UNITED STATES PATENT OFFICE

135,414

DESIGN FOR A GAME BOARD

John G. Forst, Albany, N. Y.

Application January 29, 1943, Serial No. 109,357

Term of patent 14 years

To all whom it may concern:

Be it known that I, John G. Forst, a citizen of the United States, residing at Albany, in the county of Albany and State of New York, have invented a new, original, and ornamental Design for a Game Board, of which the following is a specification, reference being had to the accompanying drawing, forming part thereof.

In the drawing:

I claim:

The ornamental design for a game board, substantially as shown.

JOHN G. FORST.
